UNITED STATES PATENT OFFICE

PER GUSTAF LAGERBÄCK, DECEASED, LATE OF STOCKHOLM, SWEDEN, BY GÖSTA
GRÖNBERG, ADMINISTRATOR, OF STOCKHOLM, SWEDEN

WASHING MACHINE

Application filed December 11, 1930, Serial No. 501,709, and in Sweden December 18, 1928.

Washing machines for household use are known which consist of a vessel and an agitator movable up and down in said vessel to effect a circulation of the washing liquid 5 through the clothes to be washed.

Heretofore, it has been customary in operating washing machines from electric motors, as are commonly employed for this class of service, to employ mechanical reducing gears, 10 in as much as the usual motor speed is about 1800 R. P. M. while the motion of the reciprocating agitator should be about 60 strokes per minute, or less.

The principal object of this invention is 15 to provide a simple and reliable form of power transmission device for washing machines having a reciprocating agitator or washing organ operated from an electric motor.

20 A further object of the invention is to make it possible to utilize the usual household vacuum cleaner as a primary power source for the operation of the washing machine.

25 Another object is the provision of means to control the operation of the power transmission device in a simple manner.

The invention consists, chiefly in the combination with a household washing machine 30 of the kind described, of a vacuum piston machine having a reciprocating piston supporting the agitator of the washing machine, said vacuum piston machine being adapted to be operated by the atmospheric pressure 35 against a vacuum generated by means of an electric fan. Preferably the electrically operated fan of a usual household vacuum cleaner when available is used for such purpose as it is of the proper size and its use 40 will save the costs of a separate primary motor.

In the accompanying drawing one embodiment of the invention is shown in vertical central section.

45 Referring to the drawing, 1 is a vessel for the washing liquid and the clothes to be washed and 2 is a cover on said vessel. On said cover the cylinder 4 of a vacuum motor is secured by means of uprights 3. A piston 5 provided in said cylinder supports by means

of rods 6 an agitator 7 in the vessel 1. On the top of the cylinder a housing 16 is secured, said housing having a conical boring 17 and adapted to form a coupling means for connecting the flexible suction pipe of an electrically operated vacuum cleaner or other vacuum conduit from an electrically operated fan to the working chamber of the cylinder. The chamber below the piston is in constant connection with the atmosphere 60 through openings 21 in the cylinder wall. The piston 5 has an opening 8 controlled by a valve 10 which is loaded by a pressure spring 9. The tension of said spring is adjusted in such manner that the spring is 65 not capable of opening the valve when the valve is closed and a vacuum is maintained in the working chamber of the cylinder. The stem 11 of the valve 10 is adapted to cooperate with a stop 12 in the uppermost position 70 of the piston so that the valve is partly opened when the stem 11 strikes against the stop, air being thus admitted into the cylinder whereby the vacuum is reduced. The valve 10 can then be completely opened by the action of 75 the spring 9. In the lowermost position of the piston the valve 10 cooperates with a stop 13 which causes a partial closing of the valve and a partial restoration of the vacuum in the cylinder when the valve strikes against 80 said stop whereupon the valve is completely closed by the suction action against the action of the spring 9.

In combination with the housing 16 means 85 for controlling the operation of the vacuum motor are provided. For such purpose the housing 16 is provided with leaking openings 18 forming an open connection to the atmosphere which allows air to flow into the suction pipe so as to reduce the vacuum in the working chamber of the cylinder to a proper value during the upward stroke of the piston. The housing 16 has an outer screw thread on which a threaded shell 20 is provided in such manner that the leaking openings 18 in the wall of the housing may be covered more or less to control the suction action from the suction pipe on the vacuum motor. The shell 20 is provided with a set 90 95 100

screw 19 by means of which it may be locked in desired positions.

Under normal conditions the operation of the washing machine is as follows.

- 5 The vessel is filled to a suitable level with the washing liquor and the clothes to be washed. The cover 2 with the vacuum motor is then secured to the vessel and a suction conduit, preferably the flexible suction pipe 10 of an electrically operated vacuum cleaner, is coupled to the vacuum motor by means of the housing 16. A vacuum is thus generated in the working chamber of the cylinder 4, causing the piston 5 with the agitator 7 to 15 move upwards. When the piston reaches its uppermost position the valve stem 11 strikes against the stopper 12, thus causing the valve 10 to be opened as above explained whereby the atmospheric air obtains free access to the 20 working chamber of the cylinder and the vacuum in said chamber is substantially removed. On account of its own weight and the weight of the agitator 7 the piston 5 now sinks down towards its lower-most position 25 and when said position is reached the valve 10 strikes against the stopper 13 whereby the valve is closed. The working chamber above the piston is now again evacuated by the continued suction action from the suction 30 conduit so that the piston 5 and the agitator are again raised towards the uppermost position whereupon the described cycle is repeated. The operation of the vacuum motor is in this manner continued until the clothes 35 have been sufficiently washed.

If the suction action from the vacuum conduit connected to the housing 16 of the vacuum cylinder is too strong the operation of the vacuum motor will not be satisfactory 40 and especially the valve 10 will not be safely closed in the lower-most position of the piston. To remove this drawback it is sufficient to increase the openings 18 by screwing up the shell 20 until the suction action 45 on the piston is sufficiently decreased. If on the other hand the suction action is too weak the number of strokes per minute will decrease or the piston will rest in its lower-most position. In such case the openings 50 18 are reduced by screwing down the shell 20 until the suction action on the piston increases in the desired degree.

The invention is not limited to the means described and shown in the drawing for controlling the suction action on the piston in as much as any adjustable valve construction may be used for such purpose.

What is claimed is:—

- 60 1. A washing machine, comprising a vessel, a cover on said vessel, an agitator in said vessel, a motor cylinder secured to said cover, a piston movable up and down in said cylinder and supporting the agitator, means to alternately connect the working chamber 65 of the cylinder with the atmosphere and to

shut off such connection, and a housing on the cylinder provided with means for operatively connecting the working chamber of the motor cylinder with a vacuum conduit.

2. A washing machine, comprising a vessel, a cover on said vessel, an agitator in said vessel, a motor cylinder secured to said cover, a piston movable up and down in said cylinder and supporting the agitator, a valve in said piston to alternately connect the working chamber of the cylinder with the atmosphere and to shut off such connection, and a housing on the cylinder, forming coupling means for a vacuum conduit. 70 75

3. A washing machine as set forth in claim 2 in which an adjustable opening to the atmosphere is provided in the wall of the housing. 80

4. A washing machine, comprising a vessel, a cover on said vessel, an agitator in said vessel, a motor cylinder secured to said cover, a piston movable up and down in said cylinder and supporting the agitator, a spring-loaded valve in said piston controlling an opening to the atmosphere, stops 85 cooperating with said valve to secure its opening and closing in the end positions of the piston, and a housing on the cylinder forming coupling means for a vacuum conduit and having its interior in constant connection with the working chamber of the cylinder. 90 95

In testimony whereof I have signed my name.

GÖSTA GRÖNBERG,
Administrator of Per Gustaf Lagerbäck,
Deceased.
